UNITED STATES PATENT OFFICE.

AUGUSTUS F. DONALDSON, OF TOLEDO, OHIO, ASSIGNOR TO THE BUNTING BRASS & BRONZE COMPANY, OF TOLEDO, OHIO, A CORPORATION OF OHIO.

BROACHING MACHINE.

Application filed February 13, 1922. Serial No. 536,056.

To all whom it may concern:

Be it known that I, AUGUSTUS F. DONALDSON, a citizen of the United States, and a resident of Toledo, in the county of Lucas and State of Ohio, have made an Invention 5 Appertaining to a Broaching Machine; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification:

15 My invention has for its object to provide a broaching machine for efficiently broaching bushings. It particularly has for its object to provide a machine wherein substantially perfect bushings may be rapidly 20 broached.

By my invention is provided a means for securely holding the bushings during the broaching operation so that the cylindrical surfaces of the finished bushing will be substantially perfect in their concentricity notwithstanding the elasticity of the metal of 25 which the bushing is formed. It also provides means for rapidly placing the bushings in position for the broaching operations and delivering the bushings from the machine. The invention provides other features and advantages that will appear from the following description and upon examination of the drawings.

35 The invention may be contained in structures of different forms. To illustrate a practical application of the invention I have selected a particular construction containing the invention as an example of such 40 structures, and shall describe it hereinafter. The structure selected is illustrated in the accompanying drawings.

Figure 1 of the drawings is a side view of the machine shown partly in section. Fig. 45 2 is a sectional view of the broaching die. Fig. 3 is a top view of a bolster plate showing a part of a positioning means for locating the bushings in position preparatory to the broaching operation. Fig. 4 is a sectional view of the machine. Fig. 5 is a detail showing the centering means for the punch of the broach. Fig. 6 is a sectional view showing the positions of a bushing and parts of the machine when the broaching 50 operation has been completed. Fig. 7 is

a sectional view taken on the line 7—7 indicated in Fig. 6, and shows the stripping means for stripping the bushings from the arbors of the machine. Fig. 8 illustrates the position of the machine and of the bushings upon the completion of the stripping 60 operation.

The broaching operations are performed in the well known punch press machine, it being provided with a ram 1 that is driven 65 by suitable gear wheels 2 in the manner well known in the art. These parts are supported and guided in their operations by a suitable frame 3 which is also provided with a bolster plate 4. The bolster plate 4 is 70 rigidly secured to the frame by any suitable means.

A pair of punches 5 are connected to the ram 1 so as to permit a very slight lateral displacement of the upper ends of the 75 punches, while the punches are held from any endwise movement or displacement relative to the ram in order to neutralize the effect of the movements of a non-aligned ram, so that the punches may be properly 80 aligned by a centering means without placing the load caused by any inaccuracy of the ram's path on the centering means, and also thereby avoiding any cramped condition of the centering means by reason of 85 the fact that a plurality of punches may be used and centered by the centering means.

The punches are secured by sleeves 75 and rings 76. Balls 77 are located within the rings and the ends of the punches are 90 held against the balls by the sleeves 75. A very slight lateral and angular play in the ends of the punches is thus provided whereby the punches can adapt themselves to an aligning or centering means.

95 The punches have an end portion 6 having diameters smaller than the body portions 7 of the punches. The ends of the punches, including the ends of the body portions 7, are located within a centering means even 100 when the ram is raised to the limit of its stroke. When the ram descends in its operation the punches pass through and are guided in their movement by the centering means.

105 The means for centering the punches comprises a cross bar 8 having bored bosses 9. The bosses are also provided with slots 10 that form channels on the inside of the bosses. Guide blocks 11 are secured in the 110

channels 10 by means of plates 12 that are secured by screws 13 that close the ends of the slots or channels. The blocks 11 are adjustably positioned within the bosses by 5 means of the screws 14 which also operate to hold the blocks 11 in position. The blocks 11 are adjusted so as to hold the punches in position with reference to the other parts of the mechanism, as herein- 10 after described.

The cross bar 8 is secured to the bolster plate 4 by means of heavy blocks 15 and screws 16, and at a distance from the bolster plate that is slightly greater than the 15 length of the bushings to be broached, whereby the centering means for the punches is brought very close to the work during the broaching operation.

A pair of dies comprising a cutting ring 20 21 and a compacting ring 22 is secured in the bolster plate 4. They are secured in position by means of sleeves 17, the bushings 18 located within the sleeves 17 and clamping rings 19 that are secured to the 25 bolster plate by the clamps 20. The sleeves 17 and the bushings 18 are provided with suitable shoulders that register with shoulders formed in the bolster plate and in the sleeves 17 to support the broaching die and 30 to carry the end thrust or pressure that occurs during the broaching operations. The sleeves 18, being a perfect sliding fit on the arbors 25, serve also to guide the arbor while a bushing is passing through 35 the dies, and firmly maintain the positions of the arbor concentric with the cutting and compacting dies.

The cutting ring 21 is located above the compacting ring 22 and has a substantially 40 square cutting edge 23. The inner surface of the compacting ring is cylindrical and is somewhat smaller than the inner diameter of the cutting ring. The upper inner edge 24 of the compacting ring 22 is rounded to cause the compression of small contiguous areas of the surface of the bushing, while the remainder of the inner surface of the ring 22 operates to burnish the surface of the bushing.

In order that the exterior surfaces of the bushings may be made coaxial with the inner surfaces of the bushings, and in order that the outer surfaces of the bushings may be a truly cylindrical surface throughout its length, it is necessary to support the bushing wall during the cutting and compacting operation of the die concentric with the cutting and compacting edges of the dies and coaxial with the common axis of the said edges and the burnishing surface since bushings, particularly bronze bushings, are elastic, compressible and expandable, and consequently portions thereof will squeeze by a cutting edge without being severed from the bushing, which results in

an exceedingly irregular final product when measured in ten-thousandths of an inch. Where thin bushings are broached without supporting the walls of the bushing, a curved or "snake" bushing is produced. 70 When, however, the walls of the bushings are supported and the inner surfaces of the bushings are maintained coaxial with the die true cylindrical surfaces are formed on the exterior of the bushing. 75

To support the walls of the bushings arbors 25 are passed up through the dies and enter recesses 26 that are formed in the ends of the punches 7. The bushings 27 are placed centrally over the dies and the ends of the arbors 25 enter the lower ends of the bushings and raise them into the bosses 9 and between the centering blocks 11. The plunger 1 forces the punches 5 down and thus forces the bushings 27 over the arbors 25, and until the ends of the arbors enter the recesses 26 which they securely fit, whereupon the arbors, the punches, and the bushings move downward and the bushings are passed through the dies. 90

The arbors 25 are bolted to a movable head 28. The head 28 is guided in its movements by means of the bars 29. It is raised by means of the lever 30 that is fulcrumed on the frame 3. The lever 30 may be operated by means of the sector gears 31, one of which is connected to the lever 30, and the other to the lever 32. The lever 32 is also pivoted on the frame or on the bracket 33 secured to the frame. The lever 32 is operated by a link 34 and a cam 35. The cam 35 is connected to the crank shaft that operates the ram 1. The cam 35 is provided with a surface 36 that operates upon a roller 37 connected to the rod 34 to depress the rod 34 and thus cause the lever 30 to raise the head 28, and consequently to raise the arbors 25, the head 28 being connected to the lever 32 by a pair of links 38. If desired, the cross head 28 may be held in its raised position by spring pressed latches 39 that engage the ends of the cross head 28. The latches 39 are pivoted to the frame 3 and are spring pressed by the springs 40. The cross bar 28 is held in position while the bushings are being forced over the arbors and the ends of the arbors are fitted into the recesses 26 formed in the ends of the punches. The latches 39 are then tripped by the levers 41. The levers 41 are pivoted on the bolts 42 that thread into the head 28 and are provided with cam surfaces 43 that operate upon rollers 44. The ends of the levers 41 are elastically held by the spring pressed block 45 and are located so as to be moved downward against the block 45 by the end of the rod 46 which is secured to the ram 1. When the cross head 28 is released the arbors are moved down by the operation of the punches 7 and the 100

110 cross bar 28 is held in position while the bushings are being forced over the arbors and the ends of the arbors are fitted into the recesses 26 formed in the ends of the punches. The latches 39 are then tripped by the levers 41. The levers 41 are pivoted on the bolts 42 that thread into the head 28 and are provided with cam surfaces 43 that operate upon rollers 44. The ends of the levers 41 are elastically held by the spring pressed block 45 and are located so as to be moved downward against the block 45 by the end of the rod 46 which is secured to the ram 1. When the cross head 28 is released the arbors are moved down by the operation of the punches 7 and the 115

120 cross bar 28 is held in position while the bushings are being forced over the arbors and the ends of the arbors are fitted into the recesses 26 formed in the ends of the punches. The latches 39 are then tripped by the levers 41. The levers 41 are pivoted on the bolts 42 that thread into the head 28 and are provided with cam surfaces 43 that operate upon rollers 44. The ends of the levers 41 are elastically held by the spring pressed block 45 and are located so as to be moved downward against the block 45 by the end of the rod 46 which is secured to the ram 1. When the cross head 28 is released the arbors are moved down by the operation of the punches 7 and the 130

arbors are held in position relative to the punches by the roller 37 which moves into the channel 47 of the cam 35 which operates to lift the rod 34. This movement is 5 communicated to the cross head 28 through the levers 30 and 32 and the links 38.

The arbors 25 have portions that have differing diameters. The end portions 48 of the arbors are made so as to fit the bushings 27, preferably to tightly fit the bushings so as to firmly support the bushing wall. The arbors also have the portions 49 which fit the cylindrical surfaces of the rings 22. Thus the die coacts to hold the 10 arbors in position. The bushings 18 located in the bolster plate are made relatively long and the portions 50 of the arbors fit the bushings 18 which have diameters greater than that of the portions 49 of the arbors 15 and of the cylindrical surfaces of the rings 22. The portions 51 of the arbors are further increased in diameter and the lower ends of the arbors are provided with flanges 52 which are secured to the cross head 28 by 20 suitable bolts. By this means the arbors are securely held in position and by the stepped relation of the portions of the arbors the stability of the arbors is greatly increased, and consequently the bushings are 25 rigidly held in position in the die, particularly as against any sidewise movement of the bushings. This is, particularly, to prevent any irregularities in the finished product due to slight variations in the metal of the 30 bushings that might cause variation locally in the elasticity of the metal of the bushing.

In order to remove the bushings from the arbors after they have passed through the 35 dies the arbors are carried down so as to draw the bushings through the sleeves 18 until the bushings are engaged with the stripper 53. The stripper 53 is supported and guided by the rods 54 having the heads or 40 shoulders 55 to limit the downward movement of the stripper 53. The portions 49 and 50 of the arbors have channels 56 that extend into the said portions a depth equal to the respective differences of the radii of 45 each of said portions and the portions 48 onto which the bushings are forced. The stripper 53 is provided with prongs or fingers 58 that extend to the bottom of the channels 56. When, therefore, the arbors 50 are raised the portions 51 of the arbors engage the prongs 58 and raise the stripper along the rods 54. When, however, the arbors descend the stripper is carried down 55 until it reaches the heads 58. Upon further downward movement the arbors move along the stripper until the prongs 58 engage the bushings. The prongs will hold the bushings as the arbors descend until the arbors are withdrawn from the bushings, where- 60 upon the bushings drop from the stripper 65.

Suitable means may be provided for placing the bushings in position above the dies. In the machine shown the bushings 27 are placed in front of anvils 60 that are secured to the bolster plate 4. Two pairs 70 of spring arms 61 are secured to a bar 62 that is connected by means of a plate 63 and a bracket 64 to a reciprocable piston that is operated in the cylinder 65. The plate 63 is guided in its movements by rods 75 66 that extend through depending brackets 67. The piston may be pneumatically operated, a suitable means being provided for exhausting the air and connecting a source of air pressure supply alternately from and 80 to opposite ends of the cylinder. The cylinder is connected to a suitable two-way valve 68 by means of tubes 69. The valve 68 is operated by a sector 70 having pins 71 that are operated upon by a cam bar 72 85 to throw the sector 70 first to one position and then to another position, and back again to the first position, and so on continuously synchronously with the movements of the ram 1, and so as to cause the fingers 61 90 to move towards the anvils 60 when the ends of the punches 5 are drawn within the centering bosses 9 of the cross bar 8 and immediately causing a return movement of the fingers 61 to draw the bushings from 95 the anvils to points over the dies. In order to accomplish this synchronous movement as between the operations of the fingers 61 and the punches 5 the cam bar 72 is connected by means of a rod 74 and a bracket 100 73 to the ram 1.

In order to cause engagement of the bushings by the fingers the ends of the fingers may be provided with clutch or engaging members 74 that have surface inclined to the direction of the movements of the fingers 61 so as to cause the engaging members 74 to be spread and also to cause the engaging member 74 to seize and hold the bushings in upright positions as they are drawn 105 from the anvils to broaching positions, such as the surfaces 75 and the surfaces 76.

I claim:—

1. In a bushing broaching machine, a punch, a broaching die, a member having 115 a cylindrical surface for securely holding the bushing by engagement with one of the cylindrical surfaces of the bushing, means for operating the punch to force the bushing into engaging relation with the member and subsequently to force the bushing past the broaching die, and guide members for holding the said cylindrical surface of the bushing coaxial with the die.

2. In a bushing broaching machine, a 120 punch, a die, a member having a cylindrical surface for securely holding the bushing by engagement with one of the cylindrical surfaces of the bushing, a ram, the punch so connected to the ram as to per-

mit lateral movement of the punch relative to the ram, and to force the bushing past the die, and guide members for holding the said cylindrical surface of the bushing and the punch coaxial with the die.

3. In a bushing broaching machine, a punch for engaging the end of the bushing, a broaching die, an arbor fitting the inner cylindrical surface of a bushing, means for operating the punch to force the bushing into engaging relation with the arbor and subsequently to force the bushing past the broaching die.

4. In a bushing broaching machine, a punch for engaging the end of the bushing, a cylindrical surface cutting and compacting die, an arbor fitting the inner cylindrical surface of the bushing, means for operating the punch to force the bushing into engaging relation with the arbor and subsequently to force the bushing past the die.

5. In a bushing broaching machine, a punch, an arbor, and an exterior broaching die, a centering means located in proximity to the ends of the bushing when the bushing enters the die for holding the punch and the arbor in axial alignment.

6. In a bushing broaching machine, a punch, an arbor, a cylindrical surface cutting and compacting die, a centering means located in proximity to the ends of the bushing when the bushing enters the die for holding the punch and the arbor in axial alignment.

7. In a bushing broaching machine, a punch, an arbor and a broaching die, means for raising the arbor through the die and raising the bushing to the punch, means for operating the punch to force the bushing over the arbor and the bushing and arbor through the die.

8. In a bushing broaching machine, a punch, an arbor and a broaching die, means for raising the arbor through the die and raising the bushing to the punch, means for operating the punch to force the bushing over the arbor and the bushing and arbor through the die, a centering means for centering the punch and a centering means for centering the arbor, the said centering means for the punch and arbor being located at a distance apart substantially equal to the length of the bushing.

9. In a bushing broaching machine, a punch, an arbor and a broaching die, means for raising the arbor through the die and raising the bushing to the punch, means for operating the punch to force the bushing over the arbor and the bushing and arbor through the die, an adjustable centering means for centering the punch and a centering means for centering the arbor, the said centering means being located at a distance apart substantially equal to the length of the bushing.

10. In a bushing broaching machine, a punch, an arbor and a broaching die, a bolster plate, a bushing fitting the bolster plate and the arbor, the arbor fitting the broaching die and the bushing, a cross bar secured to the bolster plate and having adjustable blocks for securing the punch in axial alignment with the arbor, a ram, the punch connected to the ram to permit free lateral movement of the punch relative to the ram.

11. In a bushing broaching machine, a punch, an arbor and a broaching die, a bolster plate, a bushing fitting the bolster plate and the arbor, the arbor fitting the broaching die and the bushing, a cross bar secured to the bolster plate and having adjustable blocks for securing the punch in axial alignment with the arbor, the cross bar located above the broaching die a distance substantially equal to the length of the bushings, a ram, the punch connected to the ram to permit free lateral movement of the punch relative to the ram.

12. In a bushing broaching machine, an arbor and a broaching die, means for raising the arbor through the broaching die, means for operating the punch to force the bushing over the arbor, and means for lowering the arbor as the punch forces the bushing through the die.

13. In a bushing broaching machine, a punch, an arbor and a broaching die, a stripper member located below the die, means for operating the punch to force the bushings over the arbor and through the die, means for withdrawing the arbor to cause engagement of the bushing by the stripper means to remove the bushing from the arbor.

14. In a bushing broaching machine, a punch, an arbor and a broaching die, the punch having a recess fitting the end of the arbor, means for forcing the arbor through the bushing and into the recess of the punch, a centering means for holding the punch and arbor in axial alignment, means for operating the punch for forcing the bushing through the broaching die.

15. In a bushing broaching machine, a ram, a punch so connected to the ram as to permit free lateral movement of the punch relative to the ram, and having a recess, a bolster plate, a broaching die located in the bolster plate, an arbor extending through the die, means for raising the arbor to raise the bushing within the centering means of the punch, means for operating the punch to force the bushing over the arbor until the arbor engages the punch within the recess, and lowering the arbor to force the bushing through the die while the arbor is held in the recess of the punch.

16. In a bushing broaching machine, a punch having a recess in its lower end, an arbor fitting the inner cylindrical surface

of a bushing to be broached, and a sleeve surrounding the arbor and located directly below the die, the upper end of said arbor engaged and firmly held in the recess in the lower end of the punch, the lower end of the arbor being of a larger diameter than the upper end and having an accurate sliding fit in the sleeve, thus holding the arbor concentric and in perfect alignment with the cutting dies and the punch, means for operating the punch to force a bushing into engaging relation with the arbor and subsequently to force the bushing through the broaching die, while the punch, the bushing and the arbor are thus securely interlocked and guided.

17. In a bushing broaching machine, a punch having a recess in its lower end, a broaching die having cutting edge and cylindrical burnishing surface, an arbor fitting the inner cylindrical surface of a bushing to be broached, and a sleeve surrounding the arbor and located directly below the die, the upper end of said arbor engaged and firmly held in the recess in the lower end of the punch, the lower end of the arbor being of a larger diameter than the upper end and having an accurate sliding fit in the sleeve and in the burnishing surface of the die, thus holding the arbor concentric and in perfect alignment with the cutting dies and the punch, means for operating the punch to force a bushing into engaging relation with the arbor and subsequently to force the bushing through the broaching die, while the punch, the bushing and the arbor are thus securely interlocked and guided.

18. In a broaching machine, a ram, a punch so connected to the ram as to permit free lateral movement of the punch relative to the ram, and having a recess, a bolster plate, a broaching die located in the bolster plate, an arbor extending through the die, means for raising the arbor to raise the bushing within the centering means of the punch, means for operating the punch to force the bushing over the arbor until the arbor engages the punch within the recess, and lowering the arbor to force the bush-

ing through the die while the arbor is held in the recess of the punch, the centering means of the punch being located at a distance above the die substantially equal to the length of the bushing. 55

19. In a bushing broaching machine, a ram, a punch so connected to the ram as to permit free lateral movement of the punch relative to the ram, and having a recess, a bolster plate, a broaching die located in the bolster plate, an arbor extending through the die, means for raising the arbor to raise the bushing within the centering means of the punch, means for operating the punch to force the punch within the recess, and lowering the arbor until the arbor engages the punch within the recess, and lowering the arbor to force the bushing through the die while the arbor is held in the recess of the punch, the centering means of the punch being located at a distance above the die substantially equal to the length of the bushing, a stripper member located below the die for stripping the bushing from the arbor. 60 70 75

20. In a bushing broaching machine, a ram, a punch so connected to the ram as to permit free lateral movement of the punch relative to the ram, and having a recess, a bolster plate, a broaching die located in the bolster plate, an arbor extending through the die, means for raising the arbor to raise the bushing within the centering means of the punch, means for operating the punch to force the bushing over the arbor until the arbor engages the punch within the recess, and lowering the arbor to force the bushing through the die while the arbor is held in the recess of the punch, the centering means of the punch being located at a distance above the die substantially equal to the length of the bushing, a stripper member located below the die for stripping the bushing from the arbor, a feeding means for elastically engaging and positioning the bushings over the broaching die. 80 85 90 95

In testimony whereof, I have hereunto signed my name to this specification.

AUGUSTUS F. DONALDSON.
